UNITED STATES PATENT OFFICE.

WILLIAM J. O'HAIRE, OF WASHINGTON, DISTRICT OF COLUMBIA.

SUBMARINE BOAT.

No. 867,294.

Specification of Letters Patent.

Patented Oct. 1, 1907.

Application filed January 15, 1906. Serial No. 298,204.

To all whom it may concern:

Be it known that I, WILLIAM J. O'HAIRE, a citizen of the United States, residing at Washington, in the District of Columbia, have invented certain new and useful 5 Improvements in Submarine Boats; and I do declare the following to be a full, clear, and exact description of the invention, such as will enable others skilled in the art to which it appertains to make and use the same.

This invention relates to improvements in sub-marine 10 boats.

The object of the invention is to provide a boat of this character having arranged therein a water-tight compartment, in which is adapted to be placed a life boat, means being provided whereby should the sub-marine 15 boat for any reason fail to rise after being submerged, the occupants of the boat may enter the life boat and thereby escape from the sunken vessel.

With the above and other objects in view, the invention 20 consists of certain novel features of construction, combination and arrangement of parts, as will be hereinafter described and claimed.

In the accompanying drawings:—Figure 1 is a side view of a sub-marine boat, partly in section, showing the application and arrangement of the invention; Fig. 25 2 is an enlarged cross sectional view through the life boat compartment and a portion of the sub-marine vessel, showing the life boat arranged in said compartment; Fig. 3 is an enlarged detail sectional view through the trap door or hatch opening into the life boat compartment from within the sub-marine boat; and Fig. 4 30 is a detail view of the brace and its connections for supporting one of the out side doors or hatches of the life boat compartment.

Referring more particularly to the drawings, 1 35 denotes a sub-marine boat, which may be of any desired construction. In the upper portion of the boat 1, at any suitable point, preferably at the center of the same, is arranged a water-tight compartment 2 which opens through the top of the boat 1, said opening being normally closed by means of hatches 3 and 4 which when shut form a water-tight closure for the compartment 2. The meeting edges of the doors or hatches 3, and 4 are preferably beveled or mitered, and the edge of the hatch 3 is provided with a projecting flange 5 40 which overlaps and rests on the upper side of the hatch 4, as shown.

At a suitable point in the compartment is arranged a floating valve 6, said valve being here shown and is preferably located in the hatch 4, as shown. The hatch 50 4 is preferably provided with one or more supporting braces 7, said braces being hingedly connected at their lower ends in a bracket 8 secured to the inner side of the compartment 2, and at its upper end is adapted to be engaged with a socket casting 9 which is provided with 55 laterally projecting trunnions 10 adapted to engage a suitable bracket 12 secured to the under side of the

hatch 4, thereby providing a pivotal connection for the socket casting 9. The lower end of the brace 7 is provided with laterally projecting trunnions 13 adapted to engage the bracket 8, thereby pivotally connecting the lower end of the brace to the bracket. The hatches 3 and 4 are preferably of hollow construction, the outer edges of the same being beveled or inclined and adapted to engage the inclined upper portion of the inner wall of the compartment 2, as shown at 14.

Along the outer upper edges of the hatches 3 and 4 are formed lateral extensions or flanges 15, said flanges extending over on to the deck or top of the boat 1 some distance beyond the edge of the opening of the compartment 2 and are hingedly connected to the top or 70 deck of the boat at this point, thus forming a practically water-tight joint at the hinged edge of the doors.

Supported on a suitable frame or table within the compartment 2 is a life boat 16, said boat being entirely inclosed and water-tight with the exception of a hatch 75 or door-way formed in the top of the same, which is adapted to be closed by a suitable trap door or hatch 17 which when shut will form a water-tight closure for said hatch-way. On the upper side or top of the life boat adjacent to the hatch-way is secured an offset 80 apertured block 18, through which is passed a locking bolt 19. This bolt is adapted to be screwed into a threaded recess 20 formed in the adjacent engaging edge of the hatch 3, thereby securely clamping said hatch 3 into engagement with the top of the block 18 and 85 holding the former in a water-tight closed position. The lock bolt 19 is provided with a stop collar 21, which is adapted to engage the under side of the offset portion of the block 18, as shown, and is provided with a handle by which the same may be readily screwed into engagement with the threaded recess in the edge of the hatch 3.

In the bottom of the compartment 2, preferably near one end is formed a door or hatch-way 22 adapted to be closed by a hinged hatch or door 23, said hatch or door 95 being adapted when shut to form a water-tight closure for the hatch-way 22. The hatch 23 is provided on both sides with suitable fastening devices by means of which the same may be locked from within the compartment 2 or from the body of the vessel. The locking devices preferably consist of bolts 24 hingedly connected to the inner and outer side of the hatch 23, and on which are adapted to be screwed winged nuts 25. On the inner and outer sides of the floor of the compartment 2 adjacent to the edge of the hatch 23 is secured 105 bifurcated or forked hasps 26 which are adapted to be engaged with the bolts 24 on one side or the other of the hatch 23, and are held in place by the nuts 25 to securely lock the hatch in closed position. The hatch may be of any suitable shape, but is preferably elliptical and around the edges of the same is formed a laterally projecting flange which is adapted to engage the

adjacent surface of the floor of the compartment 2, thereby forming a water-tight closure for the hatch plate 23. The trap door or hatch 17 of the life boat is constructed and locked in a similar manner to that described in connection with the hatch 23 except that the hatch 17 has its locking device on the inside only.

In the bottom of the compartment 2 at any suitable point is arranged a discharge valve 27, with which is connected a drain pipe 28 leading from the bottom of the boat 1, whereby water may be drained from the compartment 2 when desired. Secured to the upper sides of the hatches 3 and 4 adjacent to the meeting edges of the same are rings 29 to which may be attached suitable cables for holding the hatches 3 and 4 in an open position, when desired.

In use, should the sub-marine boat 1 for any reason fail to rise to the surface, the crew may leave the same by entering the compartment 2 through the trap door or hatch-way 22 closing the door after them. After closing said hatch-way, the crew will enter the life boat through the door-way therein. The last man to enter said door-way will first release the hatches 3 and 4 by unscrewing the locking bolt 19 and opening the flooding valve 6, after which he enters the life boat and closes and securely locks the hatch or trap door 17. The water entering the compartment 2 through the flooding valve will float the life boat in said compartment and the pressure within said compartment will equalize or over come the pressure of water on the out side of the door or hatches 3 and 4, thus causing the same to open by reason of their hollow buoyant construction and permit the life boat to rise through the opening to the surface of the water. By hinging the hatches 3 and 4 as herein shown and described, the same will swing up and back far enough to permit the life boat to pass freely from the compartment 2 without meeting any obstructions on said doors or hatches. By the use of a life boat arranged as herein shown and described, the crew of a sunken sub-marine boat may safely leave the same.

From the foregoing description, taken in connection with the accompanying drawings, the construction and operation of the invention will be readily understood without requiring a more extended explanation.

45 Various changes in the form, proportion and the

minor details of construction may be resorted to without departing from the principle or sacrificing any of the advantages of this invention, as defined by the appended claims.

Having thus described my invention, what I claim as new and desire to secure by Letters-Patent, is,--

1. A sub-marine boat having a water-tight life boat compartment separate from the main body of the boat and opening through the top of said boat, water-tight hatches or doors to close said compartment, means to secure said door, and means whereby said compartment may be flooded, substantially as described. 55

2. A sub-marine boat having a water-tight life boat compartment separate from the main body of the boat and opening through the top of said boat, water-tight hatches or doors to close said compartment, a locking screw to engage said doors thereby securing the same in closed position, a flooding valve, and a drain valve arranged in said compartment, substantially as described. 60

3. A sub-marine boat having a water tight life boat compartment separate from the main body of the boat and opening through the top of said boat, water-tight hatches or doors to close said compartment on the outside, a trap door to afford access to said compartment from the sub-marine boat, fastening devices arranged on each side of said trap door, whereby the same may be locked from within the compartment or from within the main body of the sub-marine boat, a closed life boat arranged in said compartment, said boat having a water-tight trap door, and means operated within the life boat to hold the door 75 in closed water-tight position, substantially as described. 70

4. A sub-marine boat having a water-tight life boat compartment separate from the main body of the boat and opening through the top of said boat, hinged hatches or doors to close said compartment on the outside, said hatches or doors having laterally-projecting flanges on their outer edges to project over onto the deck or top of the sub-marine boat, a flange formed on the inner edge of one of said hatches to lap over onto the meeting edge of the other, braces pivotally connected at one end to one 85 side of said compartment and adapted to loosely engage pivoted socket castings on the inner side of the adjacent hatch or trap door, valves to flood and to drain said compartment, a closed life boat arranged therein, and means to secure said hatches or trap doors of the compartment 90 to said life boat, substantially as described.

In testimony whereof I have hereunto set my hand in presence of two subscribing witnesses.

WILLIAM J. O'HAIRE.
